UNITED STATES PATENT OFFICE.

JAMES P. RICHARDSON, OF MANILA, PHILIPPINE ISLANDS, ASSIGNOR TO ARTHUR P. O'BRIEN, OF NEW YORK, N. Y.

DEFIBRATING-MACHINE.

1,076,151.

Specification of Letters Patent.

Patented Oct. 21, 1913.

Application filed September 22, 1910, Serial No. 583,251. Renewed September 8, 1913. Serial No. 788,760.

To all whom it may concern:

Be it known that I, JAMES P. RICHARDSON, a citizen of the United States, residing at Manila, Philippine Islands, have invented a new and useful Improvement in Defibrating-Machines, of which the following is a specification.

This invention relates to an improvement in defibrating machines, particularly to that type used in removing the pulp from what is known as Manila fiber.

Manila fiber varies in length from five to twenty feet, and its commercial value depends partly upon the length of the fibers and partly upon their cleanliness; that is to say, the most valuable fiber is that which is long, unbroken and thoroughly cleaned by the removal of every particle of pulp therefrom. In machines heretofore used for the purpose of removing the pulp from the fiber, a gripper has been employed for dragging a plant section through the machine and over one or more scrapers. The strength of the fibers is not sufficient to enable them to withstand without breakage the direct hard pull set up by the gripper when a number of scrapers are used, and the resultant product of the machine is more or less broken and more or less pulp adheres to the fibers, reducing its value. In stripping the fiber from the plant section by hand, it is customary to draw the plant section across a stationary knife, a little at a time, renewing the hand grip after each drawing action. In hand stripping, clean fiber may be obtained without danger of breaking or shortening the fibers. But hand stripping is slow, and objectionable for this reason.

The main objects of the present invention are the production of a simple, compact high capacity machine in which every particle of pulp is removed from the fiber and the fiber left long and clean by an action somewhat simulating that of a hand stripper; that is to say, by repeated short pulls over the scrapers.

With these and other objects not specifically mentioned in view, the invention consists in certain constructions and combinations which will be hereinafter fully described and then specifically pointed out in the claims hereunto appended.

In the accompanying drawings which form a part of this specification and in which like characters of reference indicate

the same parts, Figure 1 is a plan view of a device constructed in accordance with the invention, Fig. 2 is a side elevation of the structure shown in Fig. 1, Fig. 3 is a sectional view taken on the line 3—3 in Fig. 1, Fig. 4 is an enlarged detail view of a part of one of the scrapers used, Fig. 5 is an enlarged detail view of another part of one of the scrapers, Fig. 6 is an enlarged detail view of one of the scraper sections showing the gripper in the act of passing the same, and Fig. 7 is an enlarged detail plan view of the forwarding gripper.

In carrying the invention into effect, there is provided a frame which may vary within wide limits. As shown, however, two side frames 1 and 2 are employed. These side frames are spaced apart by means of bolts 3 suitably secured to the frame. The frames are further spaced apart and held so spaced by two curved plates 4 and 5, one at either end of the frame.

For the purpose of forwarding a plant section to be stripped through the machine, there is provided a forwarding gripper, and this gripper may vary within wide limits. In the device selected to illustrate the invention, however, the forwarding gripper consists of two jaws 6 and 7 hinged together by means of a pintle 8 engaging lugs 9 formed on the jaw 6 and lugs 10 formed on the jaw 7. The gripping faces of these jaws are undulating in form so that a perfect grip may be had on the material forwarded. The jaws are normally held together by means of a spring 11 coiled around the pintle 8 in a well known manner.

Any suitable means may be employed for producing the forwarding movement of the gripper. As shown, the jaw 7 is provided with four laterally projecting lugs 12 which are screwed or otherwise fastened to opposite links of a pair of chains 13. The chains 13 pass over sprockets 14, 15, 16 and 17, respectively mounted on shafts 18, 19, 20 and 21, all of which are journaled in the side frames 1 and 2. The chains also pass over the curved plates 4 and 5 at opposite ends of the machine. The shafts 19 and 20 project through the side frame 1 and are provided with bevel gears 22 and 23 respectively. These gears are in mesh with bevel pinions 24 and 25, both fast on a shaft 26 which is the main power shaft of the ma-

chine, and is provided with a driving pulley 27. Similarly, the shafts 18 and 21 project through the side frame 1 and are provided with bevel gears 28 and 29 which mesh respectively with bevel pinions 30 and 31, both fast on a shaft 32 parallel with and above the main shaft 26. The shaft 32 is provided with a spur gear 33 in mesh with an idle gear 34 loose on a stud 35 secured to a bracket 36 on the frame 1. The idle gear 34 is also in mesh with a spur gear 37 fast on the main shaft 26. The shaft 26 is mounted in bearings 38, and the shaft 32 in bearings 39, all fast to the side frame 1. By the structure just described, it will be readily understood that the gripper is given a continuous forwarding movement in the direction of the arrow in Fig. 3. It is to be understood, however, that in certain constructions within the invention, a continuous movement of the forwarding gripper is unnecessary. Material to be forwarded by the gripper is placed therein at the right end of the machine, the gripper being opened by hand against the action of the spring 11 to receive it. It may be here remarked that the chains are spaced apart a sufficient distance, and the gripper is wide enough, to take and forward simultaneously three strips or sections of plant; that is to say, the gripper is about 24 inches wide. Since the material is fed into the machine at the right end and first moves along the upper run of the chains, the upper run of the chains will be hereinafter referred to as the forwarding run of the chains, and the lower run of the chains will be referred to as the return run of the chains.

For the purpose of relieving the gripper of a part of the strain in forwarding the material so that danger of breaking the fiber will be eliminated, there is provided an auxiliary forwarding device, or plurality of auxiliary forwarding devices, and this device or these devices may vary within wide limits. As shown, however, a plurality of auxiliary forwarding devices are employed, and these devices are arranged to operate in separated fixed positions, by mechanism and for reasons that will presently appear. In the device selected to illustrate the invention, there are five of these auxiliary forwarding devices, each comprising a set of four, or two pair of coöperating rollers, and all alike. Since these devices are all alike, a description of one is deemed sufficient to enable the invention to be thoroughly understood, and a detailed description of the others will therefore be omitted in the interest of brevity and clearness. Each of the auxiliary forwarding devices includes a pair of coöperating rollers 40 and 41 mounted on shafts 42 and 43 respectively. Each device further includes a second pair of rollers 44 and 45 located after the first pair

and mounted on shafts 46 and 47 respectively. The rollers 40, 41, 44 and 45 are respectively provided with cut away portions 48, 49, 50 and 51, the cut away portions of each pair being arranged to register, and the cut away portions of the two pair being arranged so that while the gripper is passing between one pair, the other pair is in engagement with the material behind the gripper, as clearly shown in Fig. 3. The shafts 42, 43, 46 and 47 project through the side frame 1 and carry respectively gear wheels 52, 53, 54 and 55. The gear wheels 52 and 53 are in mesh and the face of the wheel 52 is provided with a bevel gear 56 in mesh with a bevel pinion 57 on the shaft 32. Similarly, the gear wheels 54 and 55 are in mesh and the face of the wheel 54 is provided with a bevel gear 58 in mesh with a bevel pinion 59 on the shaft 32. The gear trains of all the auxiliary forwarding devices are alike and derive their motion from the shafts 26 and 32, as clearly shown in Figs. 1 and 2. It is thought to be unnecessary to repeat the description of these trains, and separate descriptions of each are therefore omitted. By an inspection of Fig. 3, it will be readily understood that the cut away portions of the several pairs of rollers are so positioned and timed that they will register to permit the passage of the gripper at the proper time. The first set of rollers; that is to say, the set in the upper right hand corner in Fig. 3, operates not only as an auxiliary forwarding device but also as a crushing device tending to loosen the fibers from the pulpy parts of the material operated upon. This crushing device differs in no way from the other auxiliary forwarding devices.

For the purpose of removing the pulp from the fiber of the material passed through the machine, there is provided a series of scrapers one for engaging the material behind each auxiliary forwarding device, and these scrapers may vary within wide limits. As shown, however, each scraper includes a plain knife 60 and co-operating block 61, and a serrated knife 62 and co-operating block 63, which are arranged to be successively swung apart by the gripper during the forwarding movement of the same. To this end, there is provided a pair of rods 64 journaled in the side frames 1 and 2. To the lower rod 64 is secured a frame 65 having upwardly projecting arms 66 to which is pivoted a knife support 67. This support is normally held in the position relative to the frame 65 shown in Fig. 6 by means of a flat return bend spring 68. A pin 69 engaging a slot 70 in the arm 66 limits the movement of the knife support and knife relative to the arm 66. The arm 66 is further provided with a lever 71 adapted to engage the

gripper and prevent the latter from injuring the knife while passing the scraper, as clearly shown in Fig. 6. A spring 72 serves to normally hold the arm 66 against a stop 5 73 secured to the frame of the machine. Similarly, the block 61 coöperating with the knife 60 is carried by a support 74 mounted on arms 75 carried by the upper rod 64. A spring 76 serves to normally hold the arms 10 75 against a stop 78 secured to the frame of the machine. By an inspection of Fig. 6, it will be readily understood that the gripper, during its forwarding movement, will swing the knife and coöperating block 15 out of the way and against the action of the springs 72 and 76. After the gripper has passed, the knife and block will be returned by the springs to their normal positions in engagement with the material forwarded. 20 The knife will operate to strip pulp from the under side of the plant section in the machine. The serrated knife 62 and its coöperating block 63 are mounted in precisely the same manner as the plain knife 25 and its coöperating block just described. A detailed description of the second knife mounting is therefore omitted in the interest of brevity. It may be here remarked that the object of the plain knife and its coöperating block is to roughly remove pulp from the plant section as a whole, while the object of the serrated knife and its coöperating block is to separate the fibers after the bulk of the pulp has been removed 30 35 by the plain knife. The repeated action of the several scrapers serves to entirely remove all pulp and to cleanly separate the fibers.

By an inspection of Fig. 3, it will be 40 readily understood that there is a scraping mechanism or scraper behind each of the auxiliary forwarding devices, that it is the auxiliary forwarding devices rather than the gripper which bears the greater part of 45 the strain of the material against the scrapers, thus relieving the gripper of a part of its load, and that the pulp may be scraped cleanly from the fiber by the repeated actions of the several forwarding devices and scrapers without danger of breaking 50 the fiber. The plant section is ordinarily fed into the machine pulp side down, so that the scrapers located in the path of the forwarding run of the chains remove 55 the pulp from the fiber on one side, while the scrapers located in the path of the return run of the chains scrape the thin outer skin from the other side of the plant.

In view of the foregoing, a detailed 60 description of the operation of the device is deemed unnecessary and is therefore omitted in the interest of brevity.

Changes and variations may be made in the structure by means of which the invention is carried into effect. The invention,

therefore, is not to be restricted to the precise details of the structure shown and described.

What is claimed is:

1. In a defibrating machine, the combination with a continuously traveling forwarding gripper, of a series of auxiliary forwarding devices operating in separated fixed positions each device including two pair of coöperating rollers spaced apart and partially cut away to permit the passage of the gripper between them, and a series of scrapers one for engaging the material behind each device. 70

2. In a defibrating machine, the combination with a continuously traveling forwarding gripper, of a series of auxiliary forwarding devices operating in separated fixed positions each device including two pair of coöperating rollers spaced apart and partially cut away, the cut away portion of one pair being positioned to permit the passage of the gripper while the other pair is in engagement with the material, and a series of scrapers one for engaging the material behind each device. 80 85

3. In a defibrating machine, the combination with a pair of endless chains, operating means for the chains, a gripper carried by the chains, a series of auxiliary forwarding devices operating in separated fixed positions in the path of the gripper each device including two pair of coöperating rollers spaced apart and partially cut away, the cut away portion of one pair being positioned to permit the passage of the gripper between them while the other pair is in engagement with the material, and a series of scrapers one for engaging the material behind each device. 90 95

4. In a defibrating machine, the combination with a forwarding gripper, of a crushing mechanism including two pair of rollers spaced apart and partially cut away the cut away portion of one pair being positioned to permit the passage of the gripper between them while the other pair is in engagement with material lying between them, an auxiliary forwarding device, and a scraper for engaging material behind the device. 100 110

5. In a defibrating machine, the combination with a forwarding gripper, of a series of auxiliary forwarding devices operating in separated fixed positions, a scraper for engaging one side of material forwarded and located behind one of the devices, and a scraper for engaging the other side of the material and located behind another of the devices. 115 120

6. In a defibrating machine, the combination with a pair of chains, of operating means for the chains, a gripper carried by the chains, means including a knife and coöperating block in the path of the forwarding run of the chains for scraping one side 125 130

of material forwarded by the gripper, and means including a knife and coöoperating block in the path of the return run of the chains for scraping the other side of the material.

7. In a defibrating operating machine, the combination with a continuously traveling forwarding gripper, of a series of auxiliary forwarding devices operating in separated fixed positions each including two pairs of coöperating rollers partly cut away to permit the passage of the gripper the cut away parts of the two pairs of rollers being ar-

ranged to permit the passage of the gripper through one pair while the other is in contact with the material operated upon, and a series of scrapers one engaging the material behind each device. 15

In testimony whereof, I have signed my name to this specification in the presence of 20 two subscribing witnesses.

JAMES P. RICHARDSON.
